WALLET

Leopold G. Stanley, Maplewood, N. J., assignor to
 Buxton, Incorporated, Springfield, Mass., a corporation of Massachusetts

Application October 23, 1937, Serial No. 170,509

3 Claims. (Cl. 150—38)

This invention is a novel wallet, or a case in the nature of a pocketbook adapted to contain bank notes unfolded, tickets and similar flat articles. The case hereof is composed of leather or similar limp sheet material, intended to be included in the use of the word leather, and is of the usual oblong shape, preferably taller than its width, adapted particularly for men to carry in an inner pocket.

The general object of the present invention is to afford a wallet or leather case of the pocketbook type which will be of improved convenience in use and at the same time of highly attractive appearance. A particular object is to reduce the bulk or thickness of a wallet, thereby rendering it especially convenient for certain special uses, as with evening wear, and at the same time without sacrificing security for the contents or convenience in practical use, including the insertion and removal of paper money or the like. Further objects and advantages will appear in the hereinafter following description of an illustrative embodiment of the invention or will be manifest to users of such products. To the attainment of such objects and advantages the present invention consists in the novel wallet or pocket case, and the novel features of combination, arrangement and construction, herein illustrated or described.

In the accompanying drawing Fig. 1 is a front or face view of a wallet or pocketbook embodying the present invention; and this may be considered as a front elevation, treating the wallet as standing upright, which is its natural position in use. Fig. 2 is a right hand or edgewise elevation of the wallet of Fig. 1; and Fig. 3 is a back elevation view thereof. These figures are on a small scale to indicate the general effect, the details being shown on a larger scale in the further figures.

Fig. 4 is a front elevation view of the preferred form of wallet shown in a partly opened or exposing position, thereby disclosing in part the articles contained within the wallet. This figure is substantially the face view that is presented in use when the wallet is held in the left hand, with the front wall or flap curved and held partly retracted by the left thumb. In this specification the words left and right are used in a relative sense, since, while the wallet preferably opens at the right hand edge, for manipulation of the contents at the right hand, it might conceivably be reversed in design, as for a left handed person.

Fig. 5 is a central vertical section of the wallet in closed condition, with unavoidable exaggeration of thickness dimensions and distortion of the

disposition of the layers or walls; this figure also showing the wallet supplied with contents.

Fig. 6 is a face view or elevation of the case in closed position, but with the front layer or wall broken away to show more completely the construction of the parts therebelow; the contents being omitted from this figure.

Fig. 7 is a face or front view similar in part to Fig. 4, but with an intermediate or inner layer or wall swung out, giving fuller access to the interior, as for supplying or loading the wallet with bills or bank notes.

Fig. 8 is a view similar to Fig. 6 showing a modified construction of wallet.

15 The wallet hereof comprises preferably the following flexible or limp components or layers, namely an upright oblong back wall 10, an upright front wall 11 slightly smaller than the back wall, and an intermediate wall 12 attached to the back wall.

20 In their proper position the paper money or bank notes A are placed upright, unfolded, flatly against the inner or front face of the back wall 10. The front wall 11 substantially conceals the 25 contents and is connected to the back wall along its left edge and along its bottom edge, being unconnected however at its top edge and at its right edge, so that its upper right portion is loose or free. The back and front walls 10 and 11 may thus be considered as forming a general pocket 30 space which is accessible both from the right and from the top, of dimensions to receive the paper money, bank notes, or similar objects. The left edge binding is important, giving right hand access.

35 The intermediate wall 12 is shown connected to the back wall along its right edge, extending inwardly between the back and front walls into the adjacent general pocket space. The intermediate wall may thereby be considered as defining an inner pocket between the back and intermediate walls within which the bank notes may be set to hold them against rightward extraction, while freely permitting upward extraction.

40 Around the outside margins of the wallet are suitable fastening means, which may be stitches, but are shown as consisting of flexible metallic rim fastenings 13; this being a known type of fastening or binding means consisting of short lengths or sections of sheet metal bent and crimped around the edges, preferably in a continuous line, thus securely uniting the several walls. These may be gold or silver plated.

45 It will be noted that the metallic binding means runs continuously around the entire periphery

and is not interrupted or concealed by any wall, but connects the front and intermediate walls to the back wall.

When the wallet is closed the walls 11 and 12 conceal the contents from front view. Indeed the front wall 11 alone may perform this function. The upper right portion 14 of the front wall may be swung away, that is leftward and downward, as in Figs. 4 and 7, thus sufficiently exposing the contents for ready extraction when required. The intermediate wall 12 is preferably cut away at its upper left portion, with a long sweeping curve as shown in Figs. 4, 6 and 7, thereby permitting adequate thumb room as Fig. 4 shows, for the engaging and extracting from the wallet of individual bills or bank notes.

In the preferred embodiment the intermediate wall 12 is loose and unconnected at its left and lower edges, being thus connected only at its vertical right edge. By this arrangement the intermediate wall constitutes a flap which may, without much difficulty, be worked out of its normal position in the general pocket space, and bent over rightwardly, as Fig. 7 shows, thereby rendering the general space fully open and accessible for the insertion of bills or other objects from the right hand side. By this complete access the insertion of a bunch of bank notes is facilitated, especially when they are not new or are rumpled, rendering insertion from above somewhat difficult. With the wallet in the position shown in Fig. 7 a number of bills may be inserted with a leftward and downward motion and jogged snugly into place, the intermediate wall or flap 12 being then restored to its normal interior position. With new bills this is not necessary and in the modification of Fig. 8 the intermediate wall 12^a is shown as secured internally, by either its left edge or its lower edge, being thus permanently enclosed between the front wall 11^a and the back wall 10^a.

For certain uses it is desirable to carry not only bank notes but some smaller objects such as theater tickets or a folded license, and on the front side of the intermediate wall 12 or 12^a is shown a relatively small wall 15 forming an upwardly opening pocket in a position to receive tickets and the like, which, it will be seen from Fig. 4, are rendered partly visible by the opening out of the front wall.

As already pointed out the intermediate wall 12 divides the general space into a rear pocket behind said wall and a full size space or pocket in front of such wall. While the bills are more secure in the rear pocket, the front pocket or space is available for the temporary placing of bills, for example received as change, when this is desirable to avoid delay from having to return bills to the inside or rear pocket space.

It is to be understood that matters of arrangement, design and details of structure may be variously modified within the principles of the present invention, and the claims are not intended to be limited to the disclosed structure except to the extent specified in the respective claims.

I claim:

1. An unfoldable flat pocket case of the wallet

type adapted to hold paper money bills in flat unfolded condition, said wallet when closed being of elongated oblong shape and of dimensions slightly larger in both directions than paper money bills and comprising limp or leather components as follows: (1) an upright oblong back wall of the full size of the wallet and unadapted to being folded, (2) an upright front wall connected to the back wall along its upright left and bottom edges but unconnected and loose at its top and right edges, thereby forming a general pocket space accessible from the top and right, wherein the contained bills are normally concealed but readily exposed partly to view by swinging back the free upper right corner of the front wall, and (3) an intermediate limp flap connected to the back wall along its upright right edge, and extending therefrom into and normally splitting said general pocket space, and behind which intermediate wall the bills may be set to be confined against lateral extraction in either right or left direction while leaving them readily upwardly extractable; said intermediate flap being truncated at its upper left portion, namely, approximately from its upper right corner in a generally diagonal manner presenting an edge extending leftward and downward at an incline; whereby when the upper right portion of the front wall is swung back about its diagonal extending between its upper left and lower right corners, a triangular area of the bills contained behind the intermediate flap is exposed for convenient access and endwise upward extraction of bills; and said intermediate flap being free at all except its upright edge, and thus constituting a loose flap which may be worked rightwardly out of the general pocket space to afford lateral access for the insertion of bills, and may be tucked back between such bills and the front wall, substantially as described.

2. A pocket receptacle, comprising, outer and inner substantially rectangular walls of flexible material and of substantially equal area superposed one upon the other and secured together along one side edge and one end edge to form between them a compartment for papers and the like, the remaining edges of said walls being unsecured, whereby the receptacle is open along one end and one side, and a retaining flap of flexible material hingedly connected to the other side edge of the outer wall and normally extending between said walls to retain said papers between it and the outer wall.

3. A pocket receptacle, comprising, outer and inner substantially rectangular walls of flexible material and of substantially equal area superposed one upon the other and secured together along one side edge and one end edge, said walls being unsecured along the remaining edges, the other side edge of the inner wall being spaced inwardly from the adjacent side edge of the outer wall, and a retaining flap of flexible material hingedly secured along one side edge to the last-named side edge of the outer wall and normally extending inwardly between said walls to retain between it and the outer wall such papers as may be placed in said receptacle.

LEOPOLD G. STANLEY.
